UNITED STATES PATENT OFFICE.

HENRY MOORE SUTTON, WALTER LIVINGSTON STEELE, AND EDWIN GOODWIN STEELE,
OF DALLAS, TEXAS.

AIR BAFFLE.

Application filed July 31, 1923. Serial No. 654,869.

To all whom it may concern:

Be it known that we, HENRY M. SUTTON, 5
WALTER L. STEELE, and EDWIN G. STEELE,
citizens of the United States, residing at
5 Dallas, in the county of Dallas and State of
Texas, have invented certain new and useful
Improvements in Air Baffles, of which
the following is a specification, reference
being had therein to the accompanying
10 drawing.

This invention relates to improvements
in air baffles, and is for regulating and
distributing the air within the air-chamber
of pneumatic separators, cleaners, concen- 15
trating tables and the like.

The present improvement is particularly
intended for use in connection with our
patents granted and applications pending,
and its application is shown, to so much of
20 one form as is necessary for its understand-
ing.

The machine to which the improvement
is applied, comprises an air-chamber having
its top formed of a perforate separator
25 deck over which the material passes to be
separated. Air-pressure is within the
chamber and it passes through the said deck
and acts upon the material in a manner
broadly well understood.

30 We have heretofore placed in the chamber
two air-controlling baffles, one placed a
suitable distance below the said deck and
another placed over the air-inlet opening.
We have encountered much difficulty in ob- 35
taining the proper distribution of this air
to the separating deck, and the primary ob-
ject of the present invention is to so con-
struct the baffle plates as to enable the air to
be distributed to the said deck and pass
40 through it in proper proportions and places
to accomplish an accurate separation of the
material on the deck.

The machine here shown is preferably
45 for the separation of coal, though it may
be utilized for the dry separation of any
kind of material.

A further object of the present invention
is to construct the baffle to form in-
clined openings, formed by punching the
50 metal so as to cause it to extend from the
plate at an inclination.

A further object of the present improve-
ment is to form the said baffle from material
capable of being bent to cause the openings

to be more or less open, whereby the inclina- 55
tion of the said lips can be varied with
the tongues to cause more or less of the air
to pass through. This arrangement enables
the air to be regulated according to the
conditions which are met, and to cause the 60
air to be fed through at angles to the said
deck. It also enables the lower baffle to be
controlled likewise for feeding the air to
the baffle above.

A further object of the present invention 65
is to enable the tongues of the upper baffle
below the said deck to extend in the direc-
tion opposed to the thrust of the machine,
whereby the air passing through the baffle
passes through the deck at an angle which 70
is opposed to the direction of the thrust of
the machine. This arrangement causes the
lighter materials to be held back while the
heavier materials are being thrust forward,
the said action causing the lighter and 75
heavier elements of the mass to report to the
desired portion of the deck where the sep-
aration occurs.

The said improvement not only enables 80
the upper baffle to have its tongues project
in a direction opposite to the thrust of the
machine, but it enables the tongues of the
lower baffle to extend in the opposite direc-
tion. This causes a distribution of the air 85
in the chamber below the said upper baffle.

Preferably when the machine is utilized
for the separation of materials, such as coal
and analogous materials, the separating
deck is formed of perforated material,
which enables the air from the upper baffle 90
to pass through the said perforated plate
at an angle in the same direction, thereby
acting upon the material on the deck and
effect the separation of the material.

The said improvement also enables the 95
upper baffle plate to fill the whole space
below the deck, or to leave a part of it open
for the free passage of the air without in-
terference from the said baffle plate. This
is advantageous for in the separation of coal 100
and the like, it is sometimes found advan-
tageous to leave a part of the deck at its
feed end and one side uninterrupted by the
baffle, whereby a free passage of air at those
points is permitted, which is found to be 105
very advantageous in the handling of cer-
tain kinds of material.

In Figure 1 we show a vertical sectional

view of the air-chamber of one type of our machine to which the invention is applicable.

Fig. 2 is a top plan view showing one form of the baffle applied in the carrying out of our improvement.

Fig. 3 is a top plan view of another form of our baffle plate, showing certain spaces at the feed end and one side uninterrupted.

Fig. 4 is a detached substantially full-sized view of a part of our improved baffle plate.

Fig. 5 is a transverse vertical cross-sectional view on the line 5-5 of Fig. 4, looking in the direction indicated by arrow.

Fig. 6 is a longitudinal vertical section on the line 6-6 of Fig. 4, looking in the direction indicated by arrow.

Fig. 7 is a vertical sectional view of the upper portion of the air-chamber, showing the said perforated separator deck.

Fig. 8 is a plan view of a part of the separator deck shown in Fig. 7.

Fig. 9 is a top plan view of the baffle plate, substantially full size, showing one form of adjustment of the said tongues for controlling the flow of air through the said plate.

Referring now to the drawings, 1 is a table having at its top a perforated separating deck 2, and its bottom closed as shown at 3. Connected with the said bottom is an air-duct 4, which receives its air from a fan-housing 5. It will be observed that the air-inlet supplies an air-pressure under the separating deck 2, and as in this type of machine, the table is reciprocated, the reciprocating thrust of the table being in the direction indicated by arrow in the drawings. It will thus be observed that the separating deck is under air-pressure and is given a thrust action whereby the mass to be separated is floated, so to speak, on top of the deck while it is given a thrust in the direction indicated.

Thus far we have described our type of table, and an illustration or description of the means for reciprocating the table is unnecessary to the understanding of our present invention.

Heretofore our tables have been provided with air-pressure under the separating deck and we have endeavored in various ways to show some means for controlling the flow of air to the deck, which has, to some extent, controlled the air feed. We have recognized that the proper control of air-pressure is necessary for the most efficient and best results. For a very long period of time we have made efforts to accomplish this, and have discovered the form of baffle plates, and their arrangements in the chamber which is the subject-matter of this application. Our improved baffle plate we find to meet all of the necessities of the air-control,

and that it is capable of adjustment to suit the varying conditions of the mass of material which the separating deck is acting upon.

We have herein shown one mechanical expression of our improved baffle plate which accomplishes the above results. The baffle is made from a sheet of metal 6, and this sheet of metal has struck from it a series of inclined tongues 7. In the mechanical expression of the device which we have, up to the present time, found best for carrying out our improvement, consists in stamping the said inclined tongues 7 from the plate, in parallel rows 8, the said rows extending in a direction across the thrust of the table. This arrangement may be varied, but at present we believe it to be the best to serve the purpose. It will be observed that the inclined tongues of the succeeding rows are placed out of line with the inclined tongues of the preceding rows, whereby each row has its tongue out of line with its adjacent row. By this means the air passing through the baffle is in small fixed streams since the air passing in an inclined direction from one row flows across the space between the tongues of the preceding row, and in the form shown the tongues are preferably rectangular in plan view and the tongues in one row are in a position to have the air flowing from it overlapping the tongues of the preceding row. This is clearly shown in the drawings and especially in Figs. 4 and 9.

We also call attention to the fact that in the specific form of baffle here shown, the rows of tongues are separated by transversely extending webs 9, and the tongues of each row are separated by the longitudinal webs 10, which at their opposite ends are connected with the transverse webs 9. This construction provides a good supporting means for the tongues and affords sufficient rigidity to the baffle plates under air pressure.

We also call attention to the fact that in our preferred construction the tongues project upwardly at inclinations, because we believe the best result is accomplished by that construction. However, the tongues might be depressed instead of elevated and a certain degree of the air-control be provided.

The upper baffle plates 6 and the lower baffle plate 6' are located between the air-inlet 4 and the separating deck 2. These baffle plates are furnished for the machine in the form shown in Figs. 4 and 6, which show the inclined tongues elevated slightly at their centers 7'. That is to say the machine for stamping out the baffle plates preferably form the tongues in the shapes shown in Figs. 4 and 6. When the plates are applied to the table 1, the said tongues are adapted to be adjusted to and from the

baffle plate for partially closing or for increasing the openings formed by the tongues to suit the conditions under which the table is to work.

5 By actual practice we have found it necessary to vary, for the separation of certain coal materials, the inclination of the tongues quite radically. That is to say, the said tongues 7 will be turned upward in diagonal 10 positions 11, as shown in Fig. 9, between the dotted lines *a a b b* Fig. 2, and the inclination will be varied according to the characteristics of the mass of material which is passing over the deck to be separated. The 15 lines *a a b b* are merely indicated, but we desire it to be understood that this inclined bend of the tongues will vary and may be at any desired point in the separating deck, though usually it is at or near the feed end 20 of the table where the mass of material is located.

These adjustments are easily made with the fingers bending the said tongues or lips, as the baffle plates are preferably formed 25 of thin galvanized iron.

We have also found in the actual operation of these baffle plates that in some instances it is advantageous to use a baffle plate of such size that it is not completely 30 the size of the separating deck. That is to say, a space at the feed end *c* may be left without the baffle plate, and a narrow space *d* extending along the side of the table may be left without the baffle plate. In this construction the air will freely flow through the spaces *c* and *d* for action upon the material being separated. In the space *c* where the mass of material is dumped from the feed *e*, and the mass of material comparatively thick and heavy, an unimpeded flow 40 of air to the separating deck is found essential in the proper separation of certain kinds of material. Owing to the mass of material the passage of the air is impeded 45 thereby and the whole mass is floated by the air with the lighter material passing to the top and the heavier falling down. This increased air serves to properly float the material to accomplish the beginning of the 50 separation. In the space *d*, which is the banking bar space of our patents, where the heavy material is being banked the increased flow of air is advantageous, and for that reason the air may pass through the 55 space *d* without being impeded by the baffle.

When the machine is operating upon coal, the separating deck 2 is preferably formed of material which is provided with closely arranged perforations 2', the ordinary fabric would not form a deck which would properly stand the wear and tear of the mass of coal. Furthermore, with the relatively 60 large perforations 2', the air being directed by the tongues 7 in an inclined direction 65 passes through these perforations also in

an inclined direction. This is quite advantageous in that it serves to blow back the floating lighter materials, and separates them from the heavier materials, the said lighter materials report at certain points 70 along the separating table, the reporting points varying according to the size and weight of the elements. This operation is well described in our patents and it is not necessary to be further described here. 75

Attention is called to the fact that preferably the tongues of the upper baffle plate 6, located under the separating table 2, extend at an inclination which is opposed to the direction of the thrust of the machine. 80 It will be understood from our patents that said table will decline towards the feed end so that the lighter particles which are floated in the separation flow by gravity since they are not so much affected by the thrust 85 of the table, while the heavier being affected by the thrust of the table are carried along and report at various points on the edge 90 of the table. Therefore, the extension of the tongues 7 of the baffle 6 in a direction opposed to the thrust of the table is very important in facilitating the clean separation 95 of the lighter particles from the heavier ones.

The lower baffle plate 6', which is placed 100 over the air-outlet end 4, has its tongues projecting in a direction with the thrust of the machine. This is advantageous in effecting a substantially uniform pressure of air throughout the length of the baffle plate 6. 105

While we show in the drawings only one air-outlet we desire it to be understood that where the air outlets are increased in number, there is to be a baffle plate 6' for each outlet, or a single plate extended so as to 110 cover all of the air outlets, while only a single upper baffle plate which co-operates with the deck, is used.

We desire it to be understood that the baffle 6 can be placed close to the deck 2, as 115 shown in Fig. 7, or removed therefrom as conditions may dictate, without varying from our present improvement.

We also desire it to be understood that the form of baffle plate is useful in connection with a separator deck formed of textile material, since it is the effective means for regulating the amount of air that is fed to various portions of the deck. 120

For illustration, reference is made to our Patent No. 1,315,881, dated Sept. 9th 1919, which shows means for effecting the thrust of the table, which means may be utilized in this application. The said patent also shows a plurality of plates for controlling the flow of air through the separate deck which is illustrative of one of our efforts to get the proper air-flow and the proper pressure of the air. The said patent also shows one form of separating table to which our im- 125

provement is adapted to be used. This patent also shows an air-chamber below the said separating deck and it is a type of air-pressure separating table that is referred to herein.

Our Patent 979,046 dated Dec. 20th, 1910, also shows a form of a separating deck and an air-chamber with means for controlling the air fed to the separating deck.

10 The present improvement is adapted to be used with all of these said patents and with our various other patents, and with various forms of machines and separating decks, when broadly considered.

15 Therefore, broadly we do not limit our invention to any particular type of dry separating machine. The present invention, however, is limited to dry separating machines since it is not adapted for the wet type 20 of machine.

Having thus described our invention, what we claim and desire to secure by Letters Patent is—

1. A table for dry separation of elements 25 of a mass, comprising a pervious separating deck, an air-pressure supply for floating said mass on the top of the deck, and a baffle plate between the said air-supply and the separating deck, the said baffle plate comprising inclined tongues that feed the air upward at an angle to the deck, for the purpose described.

2. A dry separating table comprising a pervious separating deck at its top, an air 35 chamber beneath the said deck, an air-pressure supply to the said chamber and a baffle plate between the air-supply and the said deck, the baffle plate having its air-passages formed by cutting inclined tongues for the purpose described.

3. A dry separating table having an end thrust, a pervious separating deck, an air chamber below the separating deck, an air-inlet to the said chamber, and a baffle plate 45 between the air inlet and the separating deck, the baffle plate having air-openings and tongues extending over the said openings at an inclination opposed to the said table thrust, for the purpose described.

50 4. A separating table comprising a pervious separating deck, an air-chamber under the said deck, an air-pressure inlet connected with the air-chamber, a baffle plate under the said separating deck having air-passages and inclined tongues extending over the air-passages, the said baffle plate being of less area than the separating deck for the purpose of leaving certain portions of the deck uninterrupted.

55 5. A separating table comprising a pervious separating deck, an air-chamber below the said deck, an air-pressure inlet connected with the said chamber, a baffle plate having openings with inclined tongues spanning the air-inlet, and a second baffle

plate having openings with inclined tongues, the said second baffle plate located between the said deck and the first-mentioned baffle plate for the purpose described.

6. A separating table having an end thrust 70 away from its feeding end, a pervious separating deck, an air-chamber below the said deck, a pressure air-inlet connected with the said chamber, a baffle plate in the air-chamber below the said deck having openings with 75 tongues inclined in a direction opposite the table thrust, and a second baffle plate covering said air-inlet, the second baffle plate having openings with tongues inclined in a direction corresponding with the said thrust 80 for the purpose described.

7. A separating table comprising a pervious separating deck, and an air-chamber below the said deck, an air-pressure inlet connected with the said deck, a baffle plate 85 covering the air-inlet having openings with inclined tongues, and a baffle plate between the said deck and the first-mentioned baffle plate, the latter plate having openings 90 with inclined tongues, the tongues of the second baffle plate extending in opposite directions whereby the air-pressure is substantially uniform in the said chamber.

8. A baffle plate for separating machines, comprising a plate having a plurality of 95 openings formed therein and a plurality of inclined tongues projecting over the said openings, the said tongues bent to various angles for varying the size of the air-openings.

9. A separating machine comprising a table having a pervious separating deck, an air-chamber below the said deck, an air-pressure inlet connected with the said chamber, and a baffle plate located in the chamber 105 between the air-inlet and the separating deck, the baffle plate having a plurality of openings formed by a plurality of inclined tongues, the said tongues arranged in parallel rows across the machine for the purpose 110 described.

10. A separating table, comprising a pervious separating deck, an air-chamber below the said deck, an air pressure supply connected with said chamber, a baffle plate located between the said supply and the said deck, the said plate having inclined tongues which are bent to vary the openings formed by them for the purpose of directing an increased air supply to certain parts of the 115 said deck.

11. A separating table, comprising a pervious separating deck, an air-chamber below the said deck, an air-pressure inlet connected with the said chamber, a baffle plate located between the deck and the said air-pressure inlet having inclined tongues, one part of the tongues being bent for directing an increased air supply to certain parts of the 125 deck, and a second baffle plate located over 130

the said air inlet in advance of the first said baffle plate and having inclined tongues for regulating the air-pressure fed to the plate above, for the purpose described.

5 12. A separating table, comprising a separating deck, an air-chamber below the said deck, an air-pressure inlet connected with the said chamber, a baffle plate in the chamber between the deck and the said air pressure inlet, the said baffle plate having inclined tongues, some of which are partly laterally bent more than others, for the purpose of directing different air pressures to different parts of the deck, for the purpose described.

10 13. A separating table having a pervious

separating deck, an air chamber below the said deck, an air pressure inlet connected with the said chamber, a baffle plate in the said chamber between the deck and the air pressure inlet, a second plate located over the air pressure inlet in advance of the first-mentioned baffle plate, the said baffle plates having inclined tongues which project at opposite angles for the purpose of controlling the pressure of air fed to the pervious deck.

20 In testimony whereof we hereunto affix our signatures.
